UNITED STATES PATENT OFFICE.

JOSHUA HOULGATE, OF FAIRFIELD, NEBRASKA.

WATER-ELEVATOR.

SPECIFICATION forming part of Letters Patent No. 349,254, dated September 14, 1886.

Application filed July 9, 1886. Serial No. 207,576. (No model.)

To all whom it may concern:

Be it known that I, JOSHUA HOULGATE, of 5
Fairfield, in the county of Clay and State of
Nebraska, have invented certain new and use-
ful Improvements in Water-Elevators; and I
do hereby declare the following to be a full,
clear, and exact description of the invention,
such as will enable others skilled in the art to
which it pertains to make and use it, reference
10 being had to the accompanying drawing,
which forms part of this specification.

My invention relates to an improvement in
water-elevators; and it consists in a bucket
provided with an air-chamber, and which is
15 covered over at its top.

The object of my invention is to provide the
bucket with an air-chamber, so as to prevent
it from sinking to the bottom of the well, and
thus bringing up sand and gravel; to cover it
20 over at its top, so as to prevent dirt from fall-
ing into the bucket while being raised, and to
form a funnel-shaped discharge at the bottom
of the bucket, so that the whole volume of wa-
ter will be discharged into a pail of ordinary
25 size.

The accompanying drawing represents a side
elevation of an apparatus embodying my in-
vention, partly in section.

A represents a well-curb, from one side of
30 which rises the standard B. Upon this stand-
ard are journaled the windlass C and the guid-
ing-pulley D. The descent of the bucket is
controlled by a friction-lever, which is made
35 to bear against the circumference of the drum
whenever so desired. The bucket G is made
long and tubular, and instead of being left
open at its top, in the usual manner, is cov-
ered over entirely by means of the air-cham-
ber H. This air-chamber is made perfectly
40 air-tight, and is of sufficient size to prevent
the bucket from sinking to the bottom of the
well, unless in very shallow water. Through
the side of the bucket, just below the air-
chamber, are made suitable air-holes, through
45 which the air displaced by the incoming wa-
ter escapes. Through the bottom of the bucket
is made a suitable opening, which is controlled
by the valve I, of any suitable construction.
This valve opens upward as the bucket de-
50 scends into the water, so as to allow the water
to freely enter the bucket, but instantly closes
when the bucket begins to rise, in order to

prevent the escape of the water until so de-
sired. Below the opening in the bottom of the
bucket is formed the funnel-shaped guide J, 55
which serves to direct the whole volume of wa-
ter directly into a pail of the ordinary size in-
stead of having it splash around in being dis-
charged, as would otherwise be the case.

Where a bucket is lowered into the well and 60
no special care is taken to prevent it from sink-
ing, and especially a bucket which has an open-
ing through its bottom, as here shown, the
bucket will descend to the bottom of the well
and draw in sand and gravel. In order to pre- 65
vent this, the air-chamber has been placed upon
the top of the bucket, as is here shown, so as to
prevent the bottom of the bucket sinking deep
enough to catch any of the impurities of the
water from the bottom of the well. This air- 70
chamber also serves to cover over the top of
the bucket, and thus prevents any dirt or im-
purities falling into the bucket while it is be-
ing raised upward, as is generally the case where
the bucket strikes against the side of the well 75
in being raised. After the bucket has been
raised above the top of the well-curb its lower
end is allowed to settle upon the hook L, se-
cured to the standard, and upon which the
water-pail is hung. The water flows from the 80
bucket into the pail in one solid stream and
without splashing around, as is generally the
case where no guide is employed, as here
shown, to prevent the splashing. After a suf-
ficient amount of water has been drawn from 85
the bucket it can be raised upward from the
hook, when the valve will automatically close,
and thus prevent the escape of any more wa-
ter.

Having thus described my invention, I 90
claim—

1. A well-bucket provided with an air-cham-
ber in its top to prevent the bucket from sink-
ing.
2. A well-bucket provided with an air-cham-
ber, and which chamber forms a covering for
the top of the bucket, substantially as de-
scribed.

In testimony whereof I affix my signature in
presence of two witnesses.

JOSHUA HOULGATE.
